No. 714,287.

Patented Nov. 25, 1902.

J. DOREY

HOD.

(Application filed Feb. 28, 1902.)

(No Model.)

UNITED STATES PATENT OFFICE.

JAMES DOREY, OF SEATTLE, WASHINGTON.

HOD.

SPECIFICATION forming part of Letters Patent No. 714,287, dated November 25, 1902.

Application filed February 26, 1902. Serial No. 95,703. (No model.)

To all whom it may concern:

Be it known that I, JAMES DOREY, a citizen of the United States, residing at Seattle, in the county of King and State of Washington, 5 have invented certain new and useful Improvements in Hods, of which the following is a specification, reference being had therein to the accompanying drawings.

This invention relates to plasterers' and 10 masons' hods, and has for its object to provide a knockdown or collapsible hod that may readily be taken apart for transportation and which upon reaching its destination may be quickly put together to form a rigid and watertight structure.

The invention consists in certain novel features of construction and combination of parts hereinafter described, illustrated in the accompanying drawings, and finally pointed out 20 in the claims.

In the said drawings, Figure 1 is a side elevation of the invention. Fig. 2 is an end view thereof. Figs. 3, 4, and 5 are perspective views, respectively, of the end and sides 25 of the hod. Fig. 6 is an enlarged cross-section on line 6-6 of Fig. 1.

Referring more particularly to the said drawings, the letters *a* and *b* represent the inclined side pieces, and *c* the end piece, of 30 the hod, having a handle *d*, by which it is carried, and a cushion-block *e*. The lower edges *ff'* of the said sides are beveled equal to the slope of the sides when the hod is assembled, and immediately above the bevel of 35 piece *a* is an integral cleat *g*, substantially triangular in cross-section and adapted to fill the angle formed between the two sides. In order, however, to make a tighter fit at this juncture, I preferably form a shoulder *g'* beneath the said cleat and offset the beveled edge *f'* of the piece *b*. Adjacent to and respectively equidistant from the rear vertical edge of each side is a groove *h*, preferably of 40 triangular section, which continues across the 45 top of cleat *g*.

The registering edges *c'* of the end piece are beveled to correspond with the aforesaid groove bottom, and they, as well as the contact-face of cleat *g*, are provided with packing-strips *i* and *k*, respectively, of rubber, 50 preferably.

The several aforementioned parts are se-

cured together by screw-threaded bolts *l*, projecting through apertures *l'* of side *a* in proximity to the lower edge of the side, and a chain 55 *m*, connecting eyebolts *n* and *n'*, fastened to each side adjacent to their tops and between the rear edges of the sides and the end piece. Upon the end piece is a bracket *p*, positioned so as to be above a right line connecting the 60 said eyebolts, so as to deflect the said chain, and consequently when a tension is put upon the chain a downward pressure is exerted through the bracket, which keeps the end piece firmly seated. A hook *m'* is included in 65 chain *m*, whereby it is readily separable for taking the hod apart. Threaded nuts *r*, having ears *r'* for turning, are provided for bolts *l* and one of the eyebolts *n*. To each of the side pieces is fixedly fastened a brace *y*, having 70 a projecting end or tang *s*, preferably tapering in a transverse direction toward the bottom, so that when forced into a socket *t* of handle *d*, provided with a hole also tapering, a supplemental clamp is formed thereby. A flat pin 75 *u*, driven through apertures *v* of said socket and tangs, key them rigidly together. Between the parts of the cushion-block *e* I insert leather or rubber strips *w* for the purpose of distributing the load between the opposite sides. The handle *d* may be made in a number of lengths, so that the entire device may be packed within a small compass 80 for easy conveyance.

Having thus described my invention, what 85 I claim as new, and desire to secure by Letters Patent, is—

1. As an improved article of manufacture, a collapsible hod, comprising sides having beveled bottom edges, a substantially triangular cleat integral with one of said sides, an end piece adapted to fit into a groove provided in the rear ends of said sides and cleat, a brace secured to each of said sides and extending therebeneath, and means to clamp 90 the aforesaid sides and end together.

2. The combination, substantially as hereinbefore described, of side *a* having a beveled lower edge *f* and a cleat *g* integral with said side, side *b* having a beveled lower edge offset to project beneath said cleat, a groove *h* adjacent to the rear edges of both of the said sides and extending across the top of said cleat, end piece *c* having opposite inclined

edges adapted to register with said grooves, packing-strips *i* and *k*, a bracket *p* on said end piece, threaded bolts *l*, chain *m*, nuts *r*, brace *y*, having pendent ends *s*, and a handle *5* provided with a socket *t*.

3. The combination in a collapsible hod, with the sides, an end, a handle and a cushion-block; of a cleat substantially triangular integral with one of said sides, packing-strips *10* on said end and said cleat, securing means for the bottom edges of the sides, securing

means for the top adjacent to the rear end adapted to engage with a bracket upon said end to keep the latter firmly seated, and said bracket, substantially as described. ¹⁵

In testimony whereof I affix my signature in presence of two witnesses.

JAMES DOREY.
